UNITED STATES PATENT OFFICE.

EMERICK BREWSTER CRAWFORD, OF NEW HAVEN, CONNECTICUT, ASSIGNOR TO THE OVEN EQUIPMENT & MFG. CO., OF NEW HAVEN, CONNECTICUT, A CORPORATION.

PIE-PLATE HOLDER FOR BAKING OVENS.

Application filed March 19, 1924. Serial No. 700,259.

To all whom it may concern:

Be it known that I, EMERICK BREWSTER CRAWFORD, a citizen of the United States, residing at New Haven, in the county of 5 New Haven and State of Connecticut, have invented a new and useful Improvement in Pie-Plate Holders for Baking Ovens; and I do hereby declare the following, when taken in connection with the accompanying 10 drawings and the characters of reference marked thereon, to be a full, clear, and exact description of the same, and which said drawings constitute part of this application, and represent in—

15 Fig. 1 a plan view of a series of pie-plate holders constructed in accordance with my invention and assembled to form a shelf-structure.

20 Fig. 2 an edge view thereof, with one of the angle-irons partly broken away.

Fig. 3 a detached perspective view of one of the holders.

Fig. 4 a view thereof in central transverse section.

25 Fig. 5 a plan view of one of the modified forms which my improved pie-plate holder may assume.

Fig. 6 a view thereof on the line 6—6 of Fig. 5.

30 My invention relates to an improved pie-plate holder applicable for use in any of the types of baking-ovens in which the pies are passed directly through, or circulated in, a heated chamber, the object being to improve 35 the nature of the baking operation and so increase the uniformity and perfection of the product and to nullify the effect of distorted pie-plates or the careless placement of the same upon the conveyor employed.

40 With these ends in view, my invention consists in a pie-plate holder for baking-ovens, the said holder being characterized by a heat-opening giving free access of heat to the bottom of the plate, and by pie-plate supports located adjacent to the said opening for supporting the plate over the same by their side or rim portions.

45 My invention further consists in a rectangular pie-plate holder having a relatively large central heat-opening, upstanding plate-supports, positioned to support a pie-plate by its side or rim over the said opening, and hand-clearance openings located between the said supports.

50 My invention further consists in a pie-plate holder for baking-ovens, having certain details of construction and combinations of parts as will be hereinafter described and particularly pointed out in the 60 claims.

55 In carrying out my invention, as herein shown, I employ a rectangular, cast or struck-up sheet-metal pie-plate holder 10 having a relatively large centrally-arranged heat-opening 11 but slightly smaller than the diameter of the plate to be used. From the edge of the said opening four equidistant segmental plate-supports 12 rise, these supports being arranged in a circle just 70 enough smaller than the diameter of the pie-plate to be used to permit its rim to rest upon them, while its body, including its sides and bottom, sets down between them over the heat-opening 11, which admits heat 75 directly to the full area of the bottom of the plate, which is very advantageous for the speedy and uniform baking of the pie, whatever its character. Clearance-spaces 13 between the supports 12 permit 80 the entrance of the hand or fingers within the circle of the supports in placing a pie-plate thereupon and in removing it therefrom. These clearance-spaces also facilitate the circulation of the heated air around 85 the sides of the plate.

90 My improved pie-plate holders are arranged, as shown, upon a pair of parallel angle-irons 14 to which they are secured by bolts 15 or other means, whereby a continuous shelf of pie-plate holders is formed with the spaces between the heat-openings of the respective holders closed by the abutment of the corners thereof, so that, in case 95 the filling of any pie boils or slops over, it will be caught and prevented from dripping onto the pies on a shelf below. The shelf may be fixed to an endless carrier or swung from an endless carrier, according to 100 the type of baking-oven used. Between the supports 12, guard-flanges or fenders 16 rises slightly into the hand-clearance spaces 13, so as to prevent the accidental flowage 105 of any escaped pie material into the heat-openings 11.

110 In Figs. 5 and 6 of the drawings, I have shown a modified pie-plate holder embodying my invention but designed to accommodate a range of pie-plate sizes. This modified holder 17 is rectangular in form and

has a large central heat-opening 18 into which project four equidistant, skeleton supports, each comprising three upstanding, segmental flanges 19, 20 and 21, decreasing in height from the outside of the circle inward, and respectively curved and spaced so as to support by their edges three standard sizes of pie-plates. The triple supports described are separated from each other by hand clearance-spaces 22, corresponding to the spaces 13 before described.

Under my invention, the pie-plates are supported entirely by their rims or on points adjacent thereto, rather than by their bottoms, which is the common practice, so that all danger of tipping or rocking, due to deformed or uneven bottoms is avoided, as well as the time and labor required to properly locate such plates on baking-oven shelves and to shim them thereupon.

My invention also avoids what hitherto has been a source of great trouble and annoyance, and the production of many disfigured pies, due to the slopping or boiling over of the pie material, and enables the baker to use and re-use pie-plates which have had their bottoms bent out of shape and which otherwise would have to be discarded or used with expense and difficulty. Moreover, my invention is attended with great improvement in the baking of the pies, since the bottoms of the pie-plates, being entirely exposed, receive the heat direct, whereby the pies are baked more uniformly than when the plates rest upon their bottoms upon a shelf or grid. Of course, the holders might be made to support the plates by their sides, as well as by their rims, but I prefer to support them by their rims, as shown herein.

I claim:

1. A pie-plate holder for baking-ovens, having a heat-opening and upstanding supports for supporting a pie-plate thereover at points apart from its bottom, the said supports being separated by clearance-openings for the hand-placement of pie-plates upon and removal from the said supports.

2. A rectangular pie-plate holder having a centrally-arranged heat-opening and upstanding supports rising adjacent thereto for supporting a pie-plate thereover at points apart from its bottom, the said supports being separated by clearance-openings for the entrance of the hand in the placement and removal of the pie-plate.

3. A pie-plate holder for baking-ovens consisting of a rectangular plate having a large, centrally-arranged heat-opening, and a plurality of upstanding, segmental pie-plate supports separated by a plurality of clearance-openings for the access of the hand in the placement upon and removal of pie-plates from the said supports, which support it independently of its bottom over the said opening.

4. A pie-plate holder for baking-ovens, consisting of a rectangular plate having a centrally-arranged heat-opening, upstanding supports arranged about the edge thereof, clearance-openings between the said supports, and fenders located between the said supports in the said clearance-openings for preventing access thereto from the corners of the plate.

5. A shelf-structure for baking-ovens, comprising two angle irons arranged parallel with each other, and a series of rectangular pie-plate holders mounted upon the said irons with their adjacent edges abutted so as to form a continuous surface, the individual holders having a centrally-arranged heat-opening and upstanding plate-supports arranged with respect thereto to support a pie-plate thereover, and separated by clearance-spaces for the hand-placement of the pie-plates upon the said supports and their removal therefrom.

In testimony whereof, I have signed this specification in the presence of two subscribing witnesses.

EMERICK BREWSTER CRAWFORD.
